D11-11. OR D12,766 EX

UNITED STATES PATENT OFFICE.

WILLIAM MARCKSTINE, OF IRVINGTON, ASSIGNOR TO WILLIAM C. EDGE,
OF NEWARK, NEW JERSEY.

DESIGN FOR A WATCH-CHAIN.

SPECIFICATION forming part of Design No. 12,766, dated February 14, 1882.

Application filed November 2, 1881. Term of patent 14 years.

To all whom it may concern:

Be it known that I, WILLIAM MARCKSTINE, of Irvington, in the county of Essex and State of New Jersey, have invented a new and original Design for a Watch-Chain, of which the following is a specification, reference being had to the accompanying photographic illustration, making a part of this specification.

Figures 1 and 2 are photographic representations of my new design for a watch-chain.

This invention relates to a new configuration or shape of wire chain for use as watch-chains, necklaces, and the like; and it consists in forming such a chain of two braids of knitted wire braided together into one flexible structure.

In the accompanying photograph, Fig. 1

shows a braided chain of knitted wire representing my design. Fig. 2 represents the same in smaller proportions.

The two braids are shown at *a* and *b* in the photograph, each being composed of knitted wire, which gives to the completed braid the peculiar effect as though it were composed of strings of very small links locked together.

I claim—

The design for the shape or configuration of a chain, the same being composed of two strands of knitted wire braided together, substantially as shown.

WILLIAM MARCKSTINE.
